BRAKE CONTROL FOR HIGH SPEED TRAINS

Ellis E. Hewitt, Edgewood, Pa., assignor to The Westinghouse Air Brake Company, Wilmerding, Pa., a corporation of Pennsylvania

Application November 3, 1936, Serial No. 108,939

63 Claims. (Cl. 303—21)

This invention relates to brake control for high speed trains, and more particularly to a method of and apparatus for controlling the brakes on high speed trains with respect to both speed and 5 the rate of retardation of the train.

A problem of the utmost importance in the operation of the new light weight, high speed, passenger trains is that of stopping the trains from high speeds in extremely short distances. 10 Such trains travel in the neighborhood of one hundred miles per hour, or more, and since at one hundred miles per hour a train travels a distance of one hundred and forty-seven feet per second, it will be appreciated that the brakes 15 must be applied with great rapidity and to a high degree if the stopping distance is to be short.

Now it is well known that in the type of brakes now universally employed the coefficient of friction between the brake shoes and the vehicle 20 wheels is relatively low at the high speeds and relatively high at the low speeds, generally increasing gradually at first as the train decreases in speed, and then increasing rapidly beginning at some low speed. If the brakes are applied 25 to a maximum degree at a high speed, the degree must be reduced as the speed of the train diminishes or otherwise sliding of wheels will result. Wheel sliding is objectionable not only because flat spots are worn on the wheel treads, 30 but also because the retarding effect of a sliding wheel is less than that of a rolling wheel.

In order to stop the train in a short distance it is, of course, desirable that all wheels be kept 35 rolling and that the maximum braking effect permitted by the adhesion between the wheel and the rail be produced on each wheel. The degree of braking must, therefore, be regulated, as the train decreases in speed, with a view to obtaining both the maximum rate of deceleration and a 40 minimum of wheel sliding.

In the high speed trains now in operation two 45 solutions have been offered to this problem. One solution involves the employment of a device which operates in response to changes in the rate of retardation of the train to so control the degree of application of the brakes as to cause the train to be decelerated at a substantially 50 constant rate of retardation (within tolerable limits), this rate being determined as that safely permissible under predetermined track conditions. 55 This device is commonly known as a retardation controller device, or "decelakron".

The other solution to the problem involves the 55 employment of a device which operates in response to the speed of the train to reduce the

degree of application of the brakes in steps as the train speed diminishes, in a manner such that the degree of application is at all times, for given track conditions, below that which would produce wheel sliding, but high enough to 5 promptly bring the train to a stop.

Obviously, both of these solutions possess advantages peculiar and characteristic to each. That is to say, the retardation controller device, or "decelakron", possesses operating characteristics peculiar only to it, while the speed controlled device possesses advantages or characteristics peculiar only to it. To enumerate some of the principal advantages of each, the retardation controller device permits the maximum degree of 10 application of the brakes for predetermined known track conditions, regardless of the train speed, and automatically corrects for variations in load in the train between stops, that is, it permits an increased degree of braking for a heavily 15 loaded train, and correspondingly permits only a lower degree of braking for a lightly loaded train. The speed controlled device operates to modify or reduce the degree of braking before 20 excessive changes in the rate of retardation of the train take place, and also functions to produce a smooth stop even in trains having considerable slack. That is to say, whereas the 25 retardation controller device does not operate until a definite change in the rate of retardation has 30 taken place, the speed controlled device functions before the increased retardation occurs, and is, therefore, very effective in preventing excessive slack action in trains employing standard type 35 couplers between cars.

In order to secure the shortest possible stopping distances for high speed trains, it is desirable that the advantages of both the retardation controller device and the speed controlled device be incorporated in a brake equipment for such trains. 40 Accordingly, therefore, it is a principal object of the present invention to provide a brake equipment employing both a retardation controller device and a speed controlled device, in an arrangement such that the advantages of each are 45 fully realized without a sacrifice of other desirable operating features.

When in a fluid pressure brake system an application of the brakes is effected to a maximum degree, it will be obvious that the danger of wheel 50 sliding increases as the brake cylinder pressure approaches a value which produces a degree of braking in excess of that safely permissible by the adhesion between wheels and rails. There is then, for a given train speed, a brake cylinder 55

pressure below which there is little or no danger of wheel sliding or of excessive rates of retardation. The need for automatic regulation of brake cylinder pressure, therefore, is primarily 5 in the upper range of brake cylinder pressures. In order to utilize to the fullest advantage the combination of the retardation controller device and the speed controlled device, it is a further object of the present invention to provide a fluid 10 pressure brake system in which the speed controlled device has control of brake cylinder pressures over a range up to what is considered to be a moderately high value for the then existing train speed, and in which the retardation controller device has control of brake cylinder pressures over a range between this moderate value 15 and the maximum value, for the then existing train speed.

If the train is provided with ordinary couplers 20 between the cars, it is likely that considerable slack must be run in when an application of the brakes is initiated. Whether or not the slack is large or small, it is desirable that the train slack be closed up gradually so as to minimize the danger of damaging shocks. To accomplish this, the 25 brakes should be first applied to a moderately high value and then more gradually increased to the maximum value. It is a further object of this invention to provide a brake equipment in 30 which the brakes are first applied rapidly up to a predetermined degree, and then the degree increased slowly up to a maximum degree, the first or rapid portion of the application being principally under the control of the speed controlled device and the second or slow portion of the application being principally under the control of 35 the retardation controller device.

From the standpoint of safety, brake equipments for high speed trains should provide for 40 effecting applications by more than one mode of operation, as, for example, by straight air operation or by automatic operation. Moreover, provision should be made for operating the brakes from a towing vehicle in the event that 45 the train has to be towed in; or in the event that an ordinary type of locomotive has to be substituted for the special type usually employed in connection with high speed trains, then from it by operation of the usual brake valve. Accordingly, therefore, it is a yet further object of the 50 invention to provide a brake equipment embodying the features heretofore referred to, in which service applications of the brakes are normally effected by straight air operation and emergency 55 applications by automatic operation, with provision for effecting service applications also by automatic operation, either from the special high speed locomotive provided, or from a standard steam locomotive substituted for the high speed 60 locomotive.

In connection with the preceding object, it is a yet further object to subject both straight air applications and automatic emergency applications of the brakes to the joint control of the 65 retardation controller device and the speed controlled device, and to subject automatic service applications to the control of the speed controlled device only.

Yet further and more specific objects of the 70 invention, dealing with the provision of specially developed mechanisms, and particular arrangements of these and other mechanisms, will be more apparent from the following description, which is taken in connection with the attached drawings, wherein,

Figs. 1—A and 1—B, when taken together and placed end-to-end, illustrate an embodiment of the invention adapted for the head end or control car of a train.

Fig. 2 is a fragmentary view taken along the 5 line 2—2 of Fig. 1—B, illustrating a portion of the speed controlled device shown in that figure.

Fig. 3 illustrates a modification which may be made to the equipment shown in Figs. 1—A and 1—B. 10

Description of embodiment of Figs. 1—A and 1—B

Considering briefly at first the embodiment shown in these two figures, I have indicated a brake cylinder at 10, which is to be understood as 15 the usual type brake cylinder for operating a conventional type of friction brake (not shown), and while only one brake cylinder has been shown it is contemplated that in practice as many will be employed as is found desirable. A relay valve is 20 indicated at 11 for controlling the supply of fluid under pressure to and its release from the brake cylinder 10. A speed controlled device 12 controls the supply of fluid under pressure to and its release from the relay valve 11. The speed controlled device 12 is in turn in part controlled by a speed controlled switch 13, which controls a plurality of circuits closable only when a pneumatic switch device 14 operates.

The brake equipment also includes an application and release magnet valve device 15, a master switch device 16, a retardation controller device, or "decelakron", 17, an automatic valve device 18, and a brake valve device 19. A source of fluid under pressure is represented by a main 30 reservoir 20, which is intended to be maintained charged from the usual compressor (not shown).

The various control pipes include a straight air pipe 22 and a brake pipe 24. A main reservoir pipe is indicated at 25 while a so-called feed 40 valve pipe is indicated at 26, this latter pipe being connected to the main reservoir 20 by way of a feed valve device 27 of conventional design and provided for the usual purpose of such a valve device.

While the equipment illustrated is intended primarily for the head end or control car of the train, it will be hereinafter pointed out the manner in which duplicates of some of the devices and parts illustrated may be distributed throughout a train, so as to provide a complete train 50 brake equipment.

Considering now more in detail the devices above referred to, it will be noted that a number of these have been illustrated in outline form 55 only. In such instances the devices are to be considered as being of conventional design, or of a particular design described and claimed in pending applications, as will be hereinafter referred to.

The more important devices shown in outline form only will be considered first. The relay valve device 11 is preferably of the type described and claimed in my pending application Serial No. 740,202, filed August 17, 1934. The relay valve device 11 operates upon supply of fluid under pressure to pipe 30 to effect a supply of fluid under pressure from the main reservoir pipe 25 to the brake cylinder 10, to a degree dependent upon the degree of pressure in the pipe 30. Upon a 70 reduction of the pressure in the pipe 30, the relay valve device 11 correspondingly reduces the pressure in the brake cylinder 10.

The automatic valve device 18 is preferably of the familiar type having a service valve portion 75

31 and an emergency valve portion 32. As is illustrated, the automatic valve device is connected to the brake pipe 24. Upon a reduction of pressure in the brake pipe 24 at a service rate the 5 service valve portion 31 only responds to supply fluid under pressure from an auxiliary reservoir 33 to a pipe 34, to a degree dependent upon the degree of brake pipe reduction. During a service reduction in brake pipe pressure, the emergency 10 valve portion 32 does not respond.

However, upon an emergency rate of reduction in brake pipe pressure not only does the service valve portion 31 respond to supply fluid under pressure from the auxiliary reservoir 33 to the 15 pipe 34, but the emergency valve portion 32 also responds to supply fluid under pressure from an emergency reservoir 28 to a pipe 35, the supply in each instance continuing until equalization takes place between each reservoir and the pipe 20 supplied therefrom.

When the brake pipe 24 is recharged following a service application of the brakes, the service valve portion 31 operates to release fluid under pressure from the pipe 34, and to recharge the 25 auxiliary reservoir 33, in the manner well known to those skilled in the art. Upon a restoration of brake pipe pressure following an emergency reduction therein, both the service valve portion 30 31 and the emergency valve portion 32 move to release position, to release fluid under pressure from the pipes 34 and 35, respectively, and to 35 respectively recharge the reservoirs 33 and 28.

In practice, I prefer to make the auxiliary reservoir 33 considerably smaller than the emergency reservoir 28, so that, upon an emergency rate of reduction in brake pipe pressure, the service valve portion 31 can produce a moderately high pressure only in the pipe 34, whereas the emergency valve portion 32 may produce a 40 much higher pressure in the pipe 35. The purpose of this will be more apparent later.

The brake valve device 19 is preferably of the general type described and claimed in my pending application, Serial No. 105,659, filed October 15, 1936. In adapting this type of brake valve device to the brake system disclosed in the present application, I have intentionally omitted some of the pipe connections to the brake valve device. The feature of the brake valve device of importance insofar as the present brake system is concerned, is that both straight air and automatic applications of the brakes may be controlled by movement of a handle 37 in a single service application zone. This is made possible 55 by providing a selector mechanism operable by a selector lever 38. When the selector lever 38 is in a straight air position, the brake valve is conditioned to supply fluid under pressure from the feed valve pipe 26 to a control pipe 40, to a 60 degree dependent upon the degree or extent of movement of the handle 37 from its release position into the service application zone. Fluid under pressure may, therefore, be supplied to the control pipe 40 to any desired degree and may 65 be released therefrom by moving the handle 37 back to the release position. During this operation of the handle, with the selector lever 38 in the straight air position, the brake pipe 24 is maintained charged.

70 When the selector lever 38 is turned to the automatic position, the handle 37 may then be moved to a service position in the same application zone as before to reduce brake pipe pressure at a service rate, in the manner characteristic of the usual type brake valve. During this

manipulation of the handle, fluid under pressure is not supplied to the control pipe 40, and it remains connected to the atmosphere.

Regardless of whether the selector 38 is in the straight air or the automatic position, when the handle 37 is turned to an emergency position, beyond the aforesaid service application zone, the pressure in the brake pipe is reduced at an emergency rate.

Considering now the speed controlled device 10 12, this device is essentially the same as that described and claimed in my pending application, Serial No. 88,098, filed June 30, 1936, and comprises a valve section 42, a diaphragm section 43, a magnet valve section 44, and a compensating section 45.

Considering first the valve section 42, this section comprises a supply valve 46, a release valve 47 and a mechanism for operating the two valves. The supply valve 46 is urged toward seated position by a spring 48 and is adapted to be unseated by movement of a lever 49 pivotally carried on a pin 50 supported in a sliding member 51. The sliding member 51 is urged to the right by a spring 52, and slides in a bore 53 in the casing. 20

The lower end of the lever 49 engages a slide or plunger 54, which in turn engages a fluted stem 55 associated with the supply valve 46. The upper end of the lever 49 is bifurcated to receive a reduced portion 56 of a stem 57 associated with the release valve 47. The stem 57 is moved backward and forward by movement of the upper end of the lever 49. 25

When the sliding member 51 is moved to the left, and carries with it the pin 50, the lever 49 35 will first fulcrum about its lower end to actuate the released valve 47 to seated position, to close communication between chamber 58 and an exhaust port 59, and when the release valve has been thus seated, the lever 49 will fulcrum about 40 its upper end and shift the slide or plunger 54 to the left to unseat the supply valve 46 against the bias of its spring 48. Unseating of the supply valve 46 opens communication between the main reservoir pipe 25 and the chamber 58. The 45 chamber 58 is in open communication with the relay valve 11 by way of the aforementioned pipe 30, so that fluid under pressure supplied to the chamber 58 flows to the relay valve to effect the operation thereof. 50

When the sliding member 51 is actuated to the right following the aforescribed operation, it will first move to a point where spring 48 seats the supply valve 46. If no further movement takes place, the supply of fluid under pressure 55 to the chamber 58 will be lapped. However, if the sliding member 51 continues to move to the right, the upper end of the lever 59 will draw the stem 57, and consequently the release valve 47, to the right, and thereby release fluid under 60 pressure from the chamber 58 to the atmosphere, by way of the exhaust port 59.

The diaphragm section 43 is provided to effect movement of the sliding member 51 to the left. The diaphragm section comprises a series of diaphragms 60, 61, 62 and 63, spaced apart and disposed in axial relation, the effective pressure areas of the diaphragms decreasing in the order named. The diaphragms form with the casing of the mechanism a chamber 64 between the two 70 diaphragms 60 and 61, a chamber 65 between the diaphragms 61 and 62, and a chamber 66 between the diaphragms 62 and 63.

The diaphragm 60 is provided with follower plates disposed on either side thereof and indi- 75

cated at 67. The diaphragm 61 is provided with a single follower plate 68, to which the diaphragm is secured, the follower plate having an annular flange 69 and a spacing lug 70 centrally thereof. The diaphragms 62 and 63 are provided with similar follower plates indicated at 71 and 72. It will be noted that the follower plates maintain the diaphragms in spaced relation, and that the diaphragms are not connected one to 10 the other. The diaphragm 63 is provided with a second follower plate 74, which is provided with a recess 75 for a purpose which will be set forth later.

The magnet valve section 44 comprises three 15 electromagnets 76, 77 and 78, designated respectively as high speed magnet valve, intermediate speed magnet valve, and low speed magnet valve. The high speed electromagnet 76 controls the 20 operation of a double beat valve 79. The double beat valve 79 is urged toward an upper seated position by a spring 80, and to a lower seated position upon energization of the electromagnet 76. In its upper seated position the double beat valve 79 opens communication between a passage 81, 25 leading to the chamber 64 between the diaphragms 60 and 61, and the atmosphere by way of a passage containing a restriction or choke 82. In its lower seated position, the double beat valve 79 closes off this communication to the atmosphere, and opens communication between a pipe 30 and passage 83 and the aforementioned passage 81 leading to the chamber 64.

The intermediate speed electromagnet 77 controls a similar double beat valve 85. This double 35 beat valve is urged toward upper seated position also by a spring 86, and to lower seated position by the electromagnet 77 when energized. In its upper seated position the double beat valve 85 opens communication between a passage 87, leading 40 to the diaphragm chamber 65, and the atmosphere by way of a passage containing a restriction or choke 88, and a port 89. In its lower seated position, the double beat valve 85 closes this communication to the atmosphere and opens 45 communication between the aforementioned pipe and passage 83 and the passage 87 leading to the chamber 65.

The low speed electromagnet 78 controls the 50 operation of a double beat valve 90 of slightly different construction from the two formerly described double beat valves. This double beat valve is urged toward upper seated position by a spring 91 and to lower seated position by the electromagnet 78 when energized. In its lower 55 seated position, the double beat valve 90 opens communication between a passage 92, leading to the diaphragm chamber 66, and the atmosphere by way of a passage containing a restriction or choke 93. In its upper seated position, the double beat valve closes off this communication to the atmosphere and opens communication between the aforementioned passage 63 and the passage 92 leading to the chamber 66.

It will be thus observed that the three electromagnets 76, 77 and 78 control, respectively, the supply of fluid under pressure to and its release from the three diaphragm chambers 64, 65 and 66.

It will also be observed that three spring loaded check valves 95, 96 and 97 provide, respectively, a one-way communication between each of the passages 81, 87 and 92 and each of the chambers 64, 65 and 66, respectively. Each of the check valves is biased to a seated position by 75 a light spring 99, and is unseated upon a pre-

ponderance of fluid pressure acting on the valve within the seated area.

Suitably secured in the casing enclosing the compensating section 45 is a diaphragm 100, subject on its left hand side to the pressure of fluid in the chamber 98 and on its right hand side to atmospheric pressure in a chamber 101, which latter chamber is at all times open to the atmosphere by way of port 102. The diaphragm 100 is provided with follower plates 103 and 104 10 on either side thereof, the former follower plate 103 being provided with a stud portion projecting through the diaphragm and the other follower plate 104 and having disposed on the threaded end thereof a securing nut 105.

Projecting to the left of the follower plate 103 are two sets of lugs 106. Each set of lugs has secured thereto, as by a pin 107, an end of one of two levers 108. Each of the levers 108 is pivotally mounted intermediate its ends on a second pin 109 supported by one of two sets of lugs 110 projecting from a rigid portion of the casing. The extreme lower end of each of the levers 108 is connected by a common pin 113 to the lower end of an arm 111. The arm 111 is provided intermediate its ends with a pin 112 which is adapted to fit into the recess 75 of the follower plate 14 attached to the scalloped diaphragm 63.

The upper end of the arm 111 is cup shaped, as indicated at 114, so as to receive the end of a 30 stem 115. The stem 115 is provided with an enlarged portion, as illustrated, which engages a spring washer 116 bearing upon a spring 117 suitably disposed in a spring housing 118. It will thus be apparent that, as the stem 115 is actuated to the right, the spring 117 will be compressed, movement of the stem being guided by the sliding of a rounded end portion 119 of the stem in a bore 120 in the casing. The cupped end 114 of the arm 111 is maintained in alignment with the pin 115 by lugs 122 on either side of the arm.

Considering now the speed controlled switch device 13, this device comprises essentially three sets of stationary contacts 125, 126 and 127, which 45 are adapted to be engaged, respectively, by movable bridging contacts 128, 129 and 130, the three bridging contacts being disposed on a common supporting stem 131, preferably formed of insulating material as indicated.

The movable contact 128 is rigidly secured to the stem 131, while the two movable contacts 129 and 130 are loosely disposed on the stem and are movable between pairs of shoulders 132 on the stem against the bias respectively of springs 55 133 and 134, in a manner to be more fully described presently.

The stem 131 has secured thereto a disc 135 and between this disc and a portion 136 of a housing enclosing the speed controlled switch device 60 is a spring 137, which reacts against the disc 135 to urge the stem 131 downwardly. Upward movement of the stem is caused by the outward movement of fly ball weights 138 due to centrifugal 65 force. The fly ball weights 138 are pivotally mounted to a rotatable member 140 on pins 141. The rotatable member 140 is driven according to the speed of the vehicle or train by an attached shaft 142, which rotates in a stationary portion 70 143. It is to be understood that the speed controlled switch device has been shown in diagrammatic form only, for the purpose of simplification, and that, when employed in practice, a device having the usual construction characteristic 75

of centrifuge devices of this type will be employed.

Considering now the pneumatic switch device 14, this device is embodied in a casing containing therein a piston 145, subject on its lowermost side to the pressure of fluid in a chamber 146 and subject on its uppermost side to pressure of a spring 147. The piston 145 is provided with a stem 148 having secured thereto and insulated therefrom a contact 149, adapted to bridge and engage two stationary contacts 150. Upon supply of fluid at a low pressure to the chamber 146, the piston 145 moves upwardly to cause contact 149 to bridge the contacts 150, and upon release of fluid below this low pressure from the chamber 146 the spring 147 actuates the piston 145 downwardly to disengage contact 149 from the contacts 150. As is illustrated, the chamber 146 is connected to the straight air pipe 22, and operation of the switch device is, therefore, controlled by straight air pipe pressure.

Considering now the application and release magnet valve device 15, this valve device is embodied in a casing having a supply valve 151 and a release valve 152. The supply valve 151 is urged toward seated position by a spring 153, and toward unseated position by an application electromagnet 154 when energized. The release valve 152 is urged toward unseated position by a spring 155 and toward seated position by a release electromagnet 156 when energized.

When the supply valve 151 is seated and the release valve 152 is unseated, the straight air pipe 22 is in communication with the atmosphere by way of an exhaust port 157. When the release valve 152 is seated and the supply valve 151 is unseated, the communication between the straight air pipe and the atmosphere is closed and the straight air pipe is placed in communication with the feed valve pipe 26.

The master switch device 16 is embodied in a casing having suitably arranged therein in spaced relation three diaphragms indicated at 160, 161 and 162. These three diaphragms are all secured together by means of a stem 163. The stem 163 carries an electric contact 164 insulated therefrom, which is adapted to engage, upon movement of the stem 163 to the left, first a resilient stationary contact 165, and then a similar contact 166.

The diaphragm 160 has, at one side thereof, a chamber 167, which is in open communication with the straight air pipe 22. The diaphragms 161 and 162 have therebetween a chamber 168, which is in open communication with a pipe 169 leading to the retardation controller device 17. The diaphragm 162 has a chamber 170 to the other side thereof which is in open communication with a pipe 171. The chamber between the two diaphragms 160 and 161 is, at all times, open to the atmosphere, and is, therefore, at atmospheric pressure.

The diaphragms 160 and 161 are of equivalent effective pressure areas, while the diaphragm 162 has a smaller effective pressure area than either of the other two diaphragms.

Disposed in the left end of the switch device casing is a small plunger 173 urged to the right by a spring 174. When the stem 163 moves to the left, the end 175 will engage the plunger 173, whereupon the spring 174 will tend to arrest further movement of the stem to the left. At the time the stem engages the plunger, the movable contact 164 will have engaged the stationary contact 165 but will not have yet engaged the sta-

tionary contact 166. The stem will then have to compress the spring 174 to effect engagement of contact 164 with the contact 166. The purpose of this arrangement will appear more clearly later.

The retardation controller device, or decelakron, shown at 17 is embodied in a casing containing a slidable weight or body 178 movable back and forth in a right line in the direction of travel of the vehicle or train. At one end of the body is positioned a lever 179, pivotally mounted to the casing intermediate its ends at 180, and carrying at one end a roller 181 and at the other end a roller 182. The roller 181 bears against the body 178, while the roller 182 bears against the end of a slide valve 183, this slide valve controlling communication between the aforementioned pipe 169 and another pipe 184, as well as between the pipe 169 and an exhaust port 185.

A spring 186 acts upon the opposite end of the slide valve 183, and, therefore, urges the slide valve toward the left. While it has not been so illustrated, the tension on the spring 186 may be varied to suit the occasion.

The retardation controller device is disposed on the head end car in a train in a manner such that, when the train is decelerating, the resulting force of inertia acts to shift the body 178 to the left, this movement of the body being opposed by the spring 186. The spring 186 is a calibrated spring so that the degree of movement of the body 178 is proportional to the rate of deceleration of the train. At a particular rate of deceleration, the slide valve 183 will be shifted to a position where it blanks communication between pipes 169 and 184, and at a particular higher rate of deceleration to the position where the pipe 169 is connected to the exhaust port 185.

The operation of this embodiment of my invention will now be described.

Running condition

When the vehicle is running under power, or is coasting, the brake valve handle 37 is maintained in the release position. With the main reservoir 45 fully charged, fluid under pressure will be delivered at feed valve pressure to the feed valve pipe 26, from whence it will flow to the brake valve device 19, and to the chamber below the supply valve 151 in the application and release valve device 15. Fluid at main reservoir pressure will be delivered to the main reservoir pipe 25, from whence it will flow to the relay valve device 11, and to the chamber to the left of the supply valve 46 in the speed controlled device 12. 50

Within the brake valve device 19, a communication is established, in the release position of the handle 37, between the feed valve pipe 26 and the brake pipe 24, and the brake pipe will be thus charged to feed valve pressure. From the brake 60 pipe 24, fluid under pressure will flow to the automatic valve device 18, and therein to the service and emergency valve portions, and from these two valve portions, respectively, to the auxiliary reservoir 33 and the emergency reservoir 28. The entire brake system will thus be charged and become ready for operation.

As has been previously indicated, applications of the brakes may be effected by either straight air operation, or by automatic operation. In 70 addition, the maximum degree to which the brakes may be initially applied at any given time depends upon the speed of the vehicle at that time, so that, in describing the operation of the brake system illustrated, it is necessary to take 75

into account the speed of the vehicle. For the purpose of illustration, it will be assumed that the vehicle has a maximum speed of one hundred miles per hour, and in describing the operation of the brake system illustrated other speed values will be assumed to facilitate the understanding of the operation of certain of the apparatus employed.

Further, it will be assumed that the main reservoir 20 is maintained charged to a pressure value in excess of one hundred pounds (per square inch), as, for example, one hundred and twenty or one hundred and twenty-five pounds; and that the feed valve device 27, which is to be understood as being of conventional design, will deliver fluid to the feed valve pipe 26 at a pressure of one hundred and ten pounds.

Straight air service applications above sixty miles per hour

When the vehicle is traveling at a speed in excess of some chosen high speed, as, for example, sixty miles per hour, the parts of the speed controlled switch device 13 will be in the positions illustrated in Fig. 1-B. That is to say, the fly-ball weights 138 will have been moved outwardly far enough, for any speed between sixty and one hundred miles per hour, to have caused the contact 128 to engage and bridge the two contacts 125, and the contact 129 to similarly bridge and engage the contacts 126. It will be noted that contact 130 is out of engagement with the contacts 127.

Now if it is desired to effect a straight air service application of the brakes, the operator first makes certain that the selector lever 38 is in the straight air position, and then moves the brake valve handle 37 into the service application zone to a degree according to the desired degree of application of the brakes. It will be assumed that the handle 37 is moved to the extreme end of the service application zone, corresponding to a full service application, in which event fluid under pressure will be supplied to the control pipe 40 until the pressure in this pipe attains the maximum value of say one hundred pounds.

Fluid under pressure in the control pipe 40 flows to one side of a conventional type double check valve device 190, where the valve therein is shifted to lower position, and fluid under pressure then flows to the pipe 171. From the pipe 171, fluid flows directly to the chamber 170 in the master switch device 16. This flow takes place at a rapid rate so that the small diaphragm 162 responds immediately and moves the stem 163 to the left, far enough to compress the stop spring 174. The contact 164 then engages both of the stationary contacts 165 and 166. This connects a battery 191 to each of two train wires 192 and 193, energizing both the release electromagnet 156 and the application electromagnet 154. The release valve 152 is thus seated and the supply valve 151 is unseated. Fluid under pressure then flows from the feed valve pipe 26 to the straight air pipe 22. From the straight air pipe 22, fluid under pressure flows to the chamber 146 in the pneumatic switch device 14.

In the switch device 14, the piston 145 is immediately actuated upwardly at a low pressure to cause contact 149 to bridge the contacts 150. The closing of these contacts immediately energizes both the high speed electromagnet 76 and the intermediate speed electromagnet 77, by completion of two circuits from a battery 194, one of

which includes the contacts 149 and 150, conductor 195, contacts 125 and 128, and conductor 196 leading to the high speed electromagnet 76, and the other of which includes contacts 126 and 129, and conductor 197 leading to the intermediate speed electromagnet 77. The electromagnet 76 actuates the double beat valve 79 to lower seated position, and the intermediate speed electromagnet 77 actuates its double beat valve 85 also to lower seated position.

Fluid under pressure in the straight air pipe 22 may then flow through a branch pipe 193 to a conventional type double check valve device 199, where it shifts the valve therein to upper position, and flows to the aforementioned pipe 83. From the pipe 83 flow continues through the passage 83 in the speed controlled device 12, and from thence past the now opened lower seat of the double beat valve 79 to the passage 81 and diaphragm chamber 64. Fluid under pressure also flows past the open lower seat of the double beat valve 85 to the passage 87 and the diaphragm chamber 65. Similarly, fluid under pressure also flows from the passage 83 past the open lower seat of the double beat valve 90 (although the low speed electromagnet 78 is deenergized at this time) to the passage 92 and the diaphragm chamber 66. It will be observed that the passage 83 extends into the chamber 98, so that fluid under pressure is also supplied to this chamber to the right of the small diaphragm 63.

Thus upon initiating an application of the brakes when the vehicle is traveling at a speed in excess of sixty miles per hour, fluid under pressure is supplied to all of the diaphragm chambers as well as to the chamber 98 to the right of the small diaphragm 63. It has been assumed that fluid under pressure is supplied to the straight air pipe to a high degree, so that it is not necessary to consider at this time the functioning of the compensating section 45 of the speed controlled device, as this portion of the device is useful primarily in connection with low straight air pipe pressures.

Fluid pressure acting to the right and also to the left of each of diaphragms 61, 62 and 63 will render these three diaphragms ineffective, but fluid pressure acting to the right of the diaphragm 60 flexes this diaphragm to the left, and thereby shifts the sliding member 51 so as to first seat the release valve 47 and to then unseat the supply valve 46. Fluid under pressure will then flow from the main reservoir pipe 25 to the chamber 58, from whence it will flow through pipe 30 to the relay valve device 11. The relay valve device will respond to the pressure of this fluid to produce a corresponding pressure in the brake cylinder 10.

Fluid under pressure in the straight air pipe 22 also flows to the chamber 167 of the master switch 16, and acts upon the diaphragm 160 in opposition to the fluid pressure acting on the small diaphragm 162, and when the degree of pressure in the chamber 167 reaches a value which is in the same relation to the pressure in the chamber 170 as the area of the small diaphragm 162 is to the area of the diaphragm 160, the spring 174 will shift the stem 163 to the right so that contact 164 disengages from the contact 166, but holds engagement with the contact 165. The application electromagnet 154 will then be deenergized, so that the supply of fluid under pressure to the straight air pipe will be lapped. As the pressure in chamber 58 of the speed controlled device 12 attains a value equal to that

in the straight air pipe 22 and in chamber 64, diaphragm 60 will be flexed to the right far enough for supply valve 46 to be seated. The relay valve 11 will then lap brake cylinder pressure at a corresponding value.

There will thus be quickly established a moderately high degree of application of the brakes, which is not equivalent to the degree of pressure supplied to the control pipe 40, but which is proportional thereto.

Fluid under pressure supplied to the pipe 17 flows also to the pipe 184, and through the retardation controller device 17 to the pipe 169 and the chamber 168 between the diaphragms 161 and 162. But the pipe 184 contains a restriction or choke 200 which greatly retards this flow, and in addition, the pipe 169 has connected thereto a timing reservoir 201, of sufficient volume to very appreciably delay the build up of pressure in the chamber 168. Eventually and after a predetermined interval of time the pressure in the chamber 168 will attain a value equal to that in the chamber 170.

As the pressure in the chamber 168 acts upon the larger diaphragm 64, it will, at some particular value, again shift the stem 163 to the left, compressing the spring 174, to again energize the application electromagnet 154. This will result in increasing straight air pipe pressure, and correspondingly increasing brake cylinder pressure to a value which is substantially equivalent to that in the control pipe 40, since the two switch diaphragms 60 and 61 are of equal areas. It will be apparent, of course, that this increase in straight air pipe pressure will take place slowly because the pressure in chamber 168 increases slowly.

One of the reasons for quickly effecting an application of the brakes to a moderately high degree is to permit a more gradual run-in of any slack which may exist in a train to which the system has been adapted. Another reason, having to do with the functioning of the retardation controller device, will be more clear later.

It will, however, be apparent at this point that by the arrangement provided a moderately high degree of application of the brakes is quickly effected, followed immediately by a slow increase in the degree of application to a value substantially equivalent to the pressure established in the control pipe 40.

Now as the brakes are applied to the maximum degree possible for a service application, the vehicle will begin to decelerate at an increasing rate of retardation. The resulting force of inertia acts upon the retardation controller body 178 and urges it to the left. If, before the speed of the vehicle has diminished to sixty miles per hour, the rate of retardation should increase to a value such that slide valve 183 is shifted to the position where the pipe 169 is connected to the atmospheric or exhaust port 185 (which is a relatively large port), fluid under pressure will be released rapidly to the atmosphere from the chamber 168. This will, of course, result in a reduction in brake cylinder pressure, tending to arrest the increase in rate of retardation, and to possibly also diminish it. It should be noted, however, that even should the retardation controller device completely exhaust the chamber 168, it cannot reduce the degree of application of the brakes below the value corresponding to that produced by supply of fluid under pressure to the chamber 170 only. That is to say, the retardation controller device can modify the de-

gree of application of the brakes only over a limited range of brake cylinder pressures.

When the rate of retardation has decreased sufficiently, the slide valve 183 may open communication between pipes 169 and 184, so that the pressure in chamber 168 will increase, but the choke 200 and timing reservoir 201 permit only a slow increase in pressure in this chamber, so that brake cylinder pressure is increased very slowly and the liability of producing an excessive and undesirable rate of retardation is minimized.

Now as the speed of the vehicle diminishes, the speed controlled switch device 13 will act at substantially sixty miles per hour to cause the contact 128 to disengage from the contacts 125, while holding the contacts 129 in engagement with the contacts 126. The high speed electromagnet 76 will be then deenergized, and double beat valve 79 will move to its upper seated position, where it will connect the diaphragm chamber 64 to the atmosphere by way of the restriction or choke 82. Fluid under pressure will then be very slowly released from the chamber 64 to the atmosphere.

This will result in the pressure in the chamber 58 overbalancing that in the chamber 64, whereupon the release valve 47 will unseat just enough to gradually release fluid under pressure from the chamber 58 to the atmosphere until such time as the pressure remaining in the chamber 58 is balanced by the steady pressure in the chamber 65 acting on diaphragm 61, which occurs when the pressure in chamber 64 has been finally exhausted. That is to say, when the chamber 64 has been exhausted the pressure in chamber 58 will have been reduced to a value which bears to the original value the same relation as the area of the diaphragm 61 bears to the area of the diaphragm 60, assuming, of course, that there has not, in the meanwhile, occurred any change in straight air pipe pressure.

The relay valve 11 responds to the reduction of pressure in the chamber 58 to correspondingly reduce brake cylinder pressure. Due to the action of the choke or restriction 82 in permitting the pressure in chamber 64 to reduce at a slow rate only, the change in brake cylinder pressure occurs slowly so that there is no great change in the rate of retardation of the vehicle due to this change in pressure. Where the brake system is adapted to a train, this gradual change of pressure may be made to take place in close approximation to the tendency of the rate of retardation to increase due to the increasing coefficient of friction between the brake shoes and the wheels, although this may not be practicable in all instances. At any rate, the change in pressure can be readily made slow enough to keep the cars in the train bunched.

When the speed of the vehicle has diminished to a chosen intermediate speed, as, for example, thirty-five miles per hour, the speed controlled switch device 13 will operate to cause contacts 129 to disengage from the contacts 126, while holding contacts 130 and 127 disengaged, and this will deenergize the intermediate speed electromagnet 77. The double beat valve 85 will then move to upper seated position, to release fluid under pressure from the diaphragm chamber 65 to the atmosphere by way of the choke or restriction 86. In a manner similar to that described before, the pressure in the chamber 65 will be gradually reduced, whereupon the valve section 42 will operate to similarly reduce the pressure

in chamber 58 since the area of diaphragm 62 is less than that of diaphragm 61, and consequently effect a like reduction in brake cylinder pressure.

5 When the speed of the vehicle has reduced to a chosen low speed, as, for example, fifteen miles per hour, the contact 128 of the speed controlled switch device will engage the contacts 127, and thus energize by way of conductor 202 the low speed electromagnet 78. Double beat valve 99 will be then shifted to lower seated position, and thus release fluid under pressure from the chamber 66 to the atmosphere past the choke or restriction 93. This will result in a further reduction 10 in brake cylinder pressure, in the manner previously described, so that, when the chamber 66 has been finally exhausted, the pressure in the brake cylinder 10 will have attained a value 15 which is in relation to the pressure in chamber 98 as the area of the small diaphragm 63 bears to the area of the large diaphragm 60.

Now if at any time during the deceleration of the vehicle the rate of retardation should increase above that for which the retardation controller 25 spring 186 has been designed, or adjusted, the retardation controller device will operate to reduce the pressure in the switch chamber 168, to further reduce straight air pipe pressure. The pressure in the diaphragm chambers of the speed 30 controlled device 12 varies as the pressure in the straight air pipe varies, because upon decrease of pressure in the passage 83 and chamber 98, the check valves 95, 96 and 97 will unseat to permit release of fluid under pressure from each 35 of the diaphragm chambers 64, 65 and 66.

It will be seen then that a reduction in straight air pipe pressure, effected as a result of operation of the retardation controller device, will result in a similar reduction in brake cylinder 40 pressure, the retardation controller device in any case being ineffective to reduce brake cylinder pressure below a value which corresponds to the degree of pressure in chamber 170 of the master switch device, but which value bears a different 45 relation thereto for each speed range considered.

As the vehicle comes to a stop, the body 178 of the retardation controller device will assume the position illustrated, since the force of inertia acting theron is now absent, so that, if the retardation 50 controller device has previously reduced the pressure in the switch chamber 168, pressure will now be restored in a very short time. This will, of course, result in the maximum possible brake cylinder pressure for speeds below fifteen miles 55 per hour.

If now it is desired to effect a release of the brakes, the brake valve handle 37 is turned to the release position, whereupon fluid under pressure will be released from the control pipe 49 to the atmosphere. This will result in a release of 60 fluid under pressure from the two switch chambers 168 and 170, it being noted that a one-way 65 check-valve device 203 is provided to insure a prompt release of fluid under pressure from the chamber 168. Release of fluid under pressure from the two chambers 168 and 170 effects de- 70 energization of both the application electromagnet 154 and the release electromagnet 156, whereupon straight air pipe pressure will be correspondingly reduced, and thereby effecting a 75 corresponding reduction in brake cylinder pressure.

As will be obvious from the description thus far, a graduated application and a graduated re-

lease of the brakes may be effected by proper manipulation of the brake valve handle 37.

Straight air service application between speeds of thirty-five and sixty miles per hour

If at the time of initiating the application of the brakes the vehicle is traveling above thirty-five miles per hour but below sixty miles per hour, the high speed electromagnet 76 will be de-energized, due to contact 128 having previously 10 disengaged from the contacts 125. Therefore, when fluid under pressure is supplied to the straight air pipe 22 by operation of the application and release magnet valve device 15, it can flow only to the diaphragm chambers 65, 66 and 15 98. The degree of brake cylinder pressure which results, therefore, will be in proportion to straight air pipe pressure in the same relation as the area of diaphragm 61 is to the area of diaphragm 60, and will thus not be as great as that attain- 20 able above sixty miles per hour.

This degree, however, may be sufficient to cause operation of the retardation controller device 11, in which event it will, as before described, vary the pressure in the switch chamber 168 only to 25 reduce the degree of application sufficiently to prevent the rate of retardation from exceeding the desired limiting value.

Now as the speed of the vehicle diminishes to thirty-five miles per hour, the intermediate speed 30 electromagnet 77 will be deenergized, whereupon the brake cylinder pressure will be reduced in the manner already described. As the speed of the vehicle diminishes to fifteen miles per hour, a further decrease in brake cylinder pressure will 35 be effected.

The retardation controller device may, of course, operate at any time that the rate of retardation exceeds the limiting value, to reduce the pressure in the chamber 168, to in turn re- 40 duce brake cylinder pressure, but it is, of course, operable to vary brake cylinder pressure over a very limited range only, regardless of the speed range considered.

Straight air service application between speeds of fifteen and thirty-five miles per hour

If, at the time the brake application is initiated, the vehicle is traveling above fifteen miles per hour but less than thirty-five miles per hour, 50 not only will the contact 128 be out of engagement with the contacts 125, but the contact 129 will also be out of engagement with the contacts 126. Thus both the high speed electromagnet 76 and the intermediate speed electromagnet 77 will 55 be deenergized. Fluid under pressure can then only be supplied to the diaphragm chambers 66 and 98, and the degree of brake cylinder pressure produced bears to straight air pipe pressure the same relation that the area of the dia- 60 phragm 62 bears to the area of the diaphragm 60. In all other respects, the functioning of the parts of the brake system will be substantially as in the manner heretofore described.

It should, therefore, be apparent from the foregoing that the initial degree of application of the brakes is determined according to the speed range in which the vehicle is operating at the time of initiating an application of the brakes. For the higher speeds, that is, from sixty miles per hour to one hundred miles per hour, the maximum brake cylinder pressure may be produced. In an intermediate speed range, that is, from thirty-five to sixty miles per hour, only moderate- 70 ly high brake cylinder pressures can be produced. 75

In the lower speed range, that is, from fifteen to thirty-five miles per hour, only low brake cylinder pressures can be produced, and under fifteen miles per hour only very low brake cylinder pressures can be produced.

Since the brake cylinder pressures which can be produced below fifteen miles per hour are low, it is possible that the brake cylinder pressure would be insufficient in some instances to cause the brake shoes to be pulled up against the wheels. To prevent this, and to insure that at least the brake shoes will be pulled up snugly against the wheels, the compensating portion 45 has been provided.

Assuming now that fluid has been supplied to the chamber 98 to five pounds pressure only, this pressure will act upon the right side of the small diaphragm 63, and also on the left side of the diaphragm 100. If the pressure acted upon the diaphragm 63 only, it could at most produce only one or two pounds pressure in the chamber 58, which would produce a like brake cylinder pressure. This pressure is too low to pull the brake shoes up tight against the wheels. But with pressure acting upon the diaphragm 100, this diaphragm flexes to the right, thus rocking the two levers 108 about their pivot pins 109, and this moves the lower end of the arm 111 to the left, as viewed in Fig. 1-B.

The arm 111 presses its pin 112 against the follower plate 74, assisting the fluid pressure acting upon the diaphragm 63 in shifting the sliding member 51 to the left. The parts are so designed that for pressures up to five pounds in the chamber 98 the compensating mechanism acts to cause a like pressure to be produced in the chamber 58, and thus in the brake cylinder 10 also. But as the pressure in the chamber 98 exceeds five pounds, the follower plate 104 attached to the diaphragm 100 will strike lugs 204 and thereby be ineffective to produce an increase in force acting to swing the lower end of the arm 111 to the left. Moreover, the spring 117 is so designed that as the pressure in chamber 58 becomes equal to the five pounds acting on the diaphragm 100, the parts of the valve section 42 will move to lap position. The compensating mechanism, therefore, is effective only for pressures around five pounds and below.

50   Emergency application

When it is desired to effect an emergency application of the brakes, the brake valve handle 77 is turned to the emergency position, whereupon the pressure in the brake pipe 24 is released to the atmosphere at an emergency rate. At the same time, fluid under pressure is supplied to the control pipe 40 to the maximum possible degree, which will be one hundred pounds for the case assumed.

Upon an emergency reduction in brake pipe pressure, both the emergency valve portion 32 and the service valve portion 31 in the automatic valve device respond, the emergency valve portion supplying fluid under pressure to the pipe 35 leading to the double check valve device 190, and the service valve portion supplying fluid under pressure to the pipe 34 leading to the double check valve device 199.

With fluid under pressure supplied to both sides of the double check valve device 190, the valve therein will move upwardly or downwardly depending upon on which side the pressure is the greater. In practice I prefer to make emergency reservoir 28 large enough so that the pressure

supplied to the pipe 35 will be greater than that supplied to the pipe 40, as, for example, one hundred and ten pounds. Fluid under pressure in the pipe 35 may then flow through the double check valve device 190 to the pipe 171 and the chamber 170. From this point on the operation of the brake system is substantially the same as described for the full service application, brake cylinder pressure being a maximum for speeds above sixty miles per hour, and being reduced as the speed of the vehicle diminishes, and also being subject to limited control by the retardation controller 17.

Fluid under pressure supplied to the pipe 34 by the service valve 31 is of no avail at this time due to the fact that the pressure of fluid in the straight air pipe 22 and the branch pipe 198 will greatly exceed the pressure in the pipe 34, as in practice I prefer to make the auxiliary reservoir 33 comparatively small so that the ultimate pressures delivered by it can never exceed a moderately high pressure in the straight air pipe. The application will, therefore, be entirely dependent upon the pressures delivered to the pipe 35 by the emergency valve section 32.

During an emergency application, the retardation controller device 17 may function as before described for a full service application. In practice, it has been usual to have the retardation controller device adjusted to permit a certain maximum rate of retardation during service applications of the brakes, and a higher rate of retardation during emergency applications. This is accomplished by providing an adjusting mechanism which operates upon initiating an emergency application of the brakes to change the setting of the retardation controller device, such for example, as is illustrated and claimed in my pending application Serial No. 741,063, filed August 23, 1934. I have not included this adjusting feature in the present disclosure, because it forms no part of the present invention.

To effect a release of the brakes following an emergency application, the brake valve handle 37 is returned to the release position, whereupon the brake pipe is again recharged to its normal pressure. Both the emergency valve section 32 and the service valve section 31, of the automatic valve device, return to release position, where fluid under pressure is released from both the pipes 35 and 34. This, of course, results in a reduction of pressure in both switch chambers 168 and 170 to effect a full release of the brakes as heretofore described.

55   Automatic service application of the brakes

Automatic service applications of the brakes are intended to be effected only when it is impossible to effect applications by straight air operation, or when the vehicle is being towed by a standard steam locomotive or the like.

When it is desired to effect an automatic service application of the brakes, the selector lever 38 is turned to the automatic position, and the brake valve handle 37 is then turned to service position where it is left long enough to reduce brake pipe pressure to the desired degree. The reduction in brake pipe pressure which results takes place at a service rate, so that the service valve portion 31 only of the automatic valve device responds. This valve portion then supplies fluid under pressure from the auxiliary reservoir 33 to the pipe 34, the pressure of this fluid shifting the valve in double check device 191 downwardly, and fluid under pressure then flowing to the pipe 33.

If the speed of the vehicle is at this time above sixty miles per hour, fluid under pressure flows from the pipe 83 to all of the diaphragm chambers 64, 65, 66 and 98, but if the speed is lower than sixty miles per hour, the flow will be to only such chambers as are in communication with the passage 83 at that time.

It will be noted that the service valve 31 supplies fluid under pressure directly to the pipe 83, and that this supply is not under the control of the retardation controller device 17. As before indicated, the auxiliary reservoir 33 is made sufficiently small so that the pressure delivered to the pipe 34 is considerably lower than that which is usually established in the straight air pipe 22 during either a straight air service application or an emergency application. As a consequence, the need for retardation control is not of as great importance.

20 The speed controlled device 12 is, however, operative to control brake cylinder pressure during this type of application with relation to the speed of the vehicle, and functions in the manner already described.

25 When it is desired to effect a release of the brakes following this type of application, the brake valve handle 37 is returned to release position to restore brake pipe pressure. The service valve 31 then returns to release position to release fluid under pressure from the pipe 34.

Modification shown in Fig. 3

The modification shown in Fig. 3 deals with the substitution of a novel type of pilot relay valve device 210 and a standard master switch device 211 for the master switch device 16 shown in Fig. 1—A.

The master switch device 211 is preferably identical with the master switch device 16 of Fig. 1—A, except that the two diaphragms 161 and 162 of that switch device are now replaced by a single diaphragm 212, which is of the same effective pressure area as the diaphragm at the opposite end of the switch device subject to 45 straight air pipe pressure.

The diaphragm 212 may be considered as mechanically arranged similar to the diaphragm 161 in the master switch device 16, that is, it is connected to a stem 213 similar to the stem 163, and is subject on one side to fluid pressure 50 in a chamber 214. The chamber 214 is in open communication with a pipe 215 leading to the pilot relay valve device 210.

The pilot relay valve device comprises two sections, a valve section 216, and a diaphragm section 217. The valve section 216 may be identical with the valve section 42 of the speed controlled device 12 of Fig. 1—B, and the corresponding parts of the two valve devices are indicated by like numerals, the description heretofore given for the valve section 42 applying to the valve section 216.

The diaphragm section 217, of the pilot relay valve device 210, comprises two flexible diaphragms 218 and 219 of different effective pressure areas, disposed in spaced relation, the former diaphragm being provided with follower plates 220 and the latter diaphragm being provided with follower plates 221. The left hand follower plate 221 is provided with an annular flange 222 and a spacing lug 223, which maintain the two diaphragms in spaced relation. It is to be noted, however, that neither the diaphragms 70 nor their follower plates are in any way con-

nected together, that is to say, each diaphragm is independently movable.

The two diaphragms 218 and 219 coact with the casing of the valve device to form a chamber 225 between the two diaphragms, and a 5 chamber 226 to the right of the diaphragm 219. A light spring 227 in the chamber 226 holds the two diaphragms in contact.

The diaphragm chamber 225 is connected to the aforementioned pipe 169, while the chamber 10 226 is connected to the aforementioned pipe 171. The chamber 58 of the valve section 216 is connected to the chamber 214 of the master switch device 211, by way of the aforementioned pipe 215. The chamber to the left of the supply valve 15 46 is connected to the main reservoir pipe 25.

In the operation of the modification shown in Fig. 3, when fluid under pressure is supplied to the control pipe 40 or pipe 35, it will first flow rapidly by way of pipe 171 to chamber 226. The 20 pressure of this fluid will act upon the smaller diaphragm 219 to operate the valve portion 216 to supply fluid under pressure from the main reservoir pipe 25 to pipe 215 and switch chamber 214, this flow taking place at a rapid rate, so 25 that a moderately high pressure is established in the chamber 214 very quickly. The master switch device 211 will then operate the application and release magnet valve device 15, as heretofore described, to effect rapidly a brake cylinder pressure, the value of which is in proportion to the pressure in the chamber 226, of the pilot relay valve device, in the same relation that the area of the smaller diaphragm 219 bears to the larger diaphragm 218, assuming a vehicle speed 30 35 above sixty miles per hour.

Fluid under pressure supplied to the control pipe 40 and pipe 171 will also flow to the diaphragm chamber 225, by way of choke 200, pipe 184, the retardation controller device 17, and pipe 40 169. This flow will, as previously described, take place at a slow rate, and will cause the pressure in the switch chamber 214 to be gradually increased to a value substantially equivalent to the pressure in the control pipe 40. This will in turn cause the brake cylinder pressure to be increased to a corresponding degree.

It will, therefore, be observed that the arrangement shown performs the same functions as are performed by the switch device 16 of Fig. 1—A, 50 that is, first quickly effecting a moderately high degree of application of the brakes, followed by a slow increase in the degree of application until the degree of application is equivalent to the control pipe pressure.

The retardation controller device 17 is thereafter operable to control the pressure in the chamber 225, just as it was operable to control the pressure in the chamber 168 of the master switch device 16.

Adaptation of brake system to a train

While the brake system embodying the invention has been illustrated as being adapted to a single vehicle only, it may be readily adapted to 65 a train comprising a plurality of cars by merely duplicating certain of the parts shown. Each car will, of course, be equipped with one or more brake cylinders, for which one relay valve device 66 only is required. Each vehicle is preferably 70 equipped with one speed controlled device 12, although it may in some instances be found more desirable to provide one speed controlled device for two or more cars. Each speed controlled device may have its own speed controlled switch 75.

13, or one such switch may be provided for all of the speed controlled devices.

5 Each car in the train is preferably provided with an application and release magnet valve device 15, while one master switch device 16 only need be provided, preferably located on the head end or control car. The same applies for the retardation controller device 17.

10 With respect to the automatic valve device 18, since the brake pipe 24 extends throughout the train, it is preferable that one of these devices, together with the two reservoirs 28 and 33, should be provided on each car of the train. Thus it will be seen that by mere duplication 15 of certain of the parts on succeeding cars in a train, a complete brake system results.

15 Experience and preference will, of course, dictate modifications and arrangements other than those disclosed and described, so that it is not 20 my intention to be limited to the particular illustrations given, nor otherwise than by the spirit and scope of the appended claims.

Having now described my invention, what I 25 claim as new and desire to secure by Letters Patent, is:

1. The method of controlling vehicle brakes, which comprises, effecting an application of the brakes, and controlling the degree of the application jointly with respect to both speed and the 30 rate of retardation of the vehicle in a manner such that during the application the minimum degree of the application is controlled with respect to the speed and the maximum degree of the application is controlled with respect to the 35 rate of retardation.

2. The method of controlling vehicle or train brakes, which comprises, effecting quickly an application of the brakes to a predetermined degree, increasing the degree of the application more 40 slowly up to a maximum degree, controlling the degree of the application between the said predetermined degree and the said maximum degree with respect to the rate of retardation of the vehicle or train, and controlling the degree of 45 the application below the said predetermined degree with respect to the speed of the vehicle or train.

3. In a vehicle or train brake system, in combination, means for effecting an application of the 50 brakes, speed controlled means, means operated according to the rate of retardation of the vehicle or train, and means so constructed and arranged that said speed controlled means controls the degree of application of the brakes over a predetermined range and said retardation controlled 55 means controls the degree of application over a different range.

4. In a vehicle brake system, in combination, 60 means for effecting an application of the brakes to a predetermined degree, means for increasing the degree of application of the brakes to a maximum degree which is above said predetermined degree, speed controlled means for controlling the degree of application of the brakes below said 65 predetermined degree, and means operated according to the rate of retardation of the vehicle for controlling the degree of application of the brakes above said predetermined degree.

5. In a vehicle brake system, in combination, 70 means for effecting an application of the brakes, means operated according to the rate of retardation of the vehicle for controlling the degree of application of the brakes, and means operated according to the speed of the vehicle for varying 75 the range over which said retardation controlled

means may vary the degree of application of the brakes.

6. In a vehicle brake system, in combination, a 5 brake cylinder, means for effecting a supply of fluid under pressure to said brake cylinder rapidly up to a chosen value, means for increasing brake cylinder pressure slowly to a degree above said chosen value, means operated according to the rate of retardation of the vehicle for controlling brake cylinder pressures above said 10 chosen value, and speed controlling means for controlling brake cylinder pressures below said chosen value.

7. In a vehicle brake system, in combination, a 15 brake cylinder, means for effecting a supply of fluid under pressure to said brake cylinder, means operated according to the rate of retardation of the vehicle for varying brake cylinder pressure to maintain a substantially constant rate of retardation of the vehicle, and speed controlled 20 means for controlling the range over which said retardation controlled means may vary brake cylinder pressure.

8. In a vehicle brake system, in combination, a 25 brake cylinder, means for establishing a communication through which fluid under pressure is supplied rapidly to effect a rapid supply of fluid under pressure to said brake cylinder, means for establishing a different communication 30 through which fluid under pressure is supplied slowly to slowly increase the degree of the brake cylinder pressure, means operated according to the rate of retardation of the vehicle for controlling the supply of fluid under pressure through 35 said second communication, and speed controlled means for controlling brake cylinder pressure regardless of through which communication fluid under pressure is supplied to establish brake cylinder pressure.

9. In a vehicle brake system, in combination, 40 speed controlled means for controlling a communication through which fluid under pressure is supplied to effect an application of the brakes, fluid pressure operated brake control means for controlling the supply of fluid under pressure to said communication, and means operated according to the rate of retardation of the vehicle for controlling at least in part the operation of said 45 brake control means.

10. In a vehicle brake system, in combination, 50 speed controlled means for controlling the degree of application of the brakes, means including a fluid pressure operated device for controlling the operation of said speed controlled means, 55 and means operated according to the rate of retardation of the vehicle for controlling in part the supply of fluid under pressure to said fluid pressure operated device.

11. In a vehicle brake system, in combination, 60 a fluid pressure operated switch device operated upon supply of fluid under pressure thereto to effect an application of the brakes, means establishing a communication through which fluid under pressure is supplied at an unrestricted rate 65 to operate said switch device, means establishing a second and separate communication through which fluid under pressure is supplied at a restricted rate to additionally effect the operation of said switch device, and means operated according to the rate of retardation of the vehicle 70 for controlling said second communication.

12. In a vehicle brake system, in combination, 75 a brake control device having two chambers and operable upon supply of fluid under pressure to 75

either or both of said chambers to effect an application of the brakes, means for effecting a supply of fluid under pressure to both of said chambers, and means operated according to the rate 5 of retardation of the vehicle for controlling the pressure in one of said chambers.

13. In a vehicle brake system, in combination, a fluid pressure operated device having two chambers and operable upon supply of fluid under pressure to one of said chambers to effect an application of the brakes to one degree and upon supply of fluid under pressure to both of said chambers to effect an application of the brakes to a different degree, means for effecting 10 a supply of fluid under pressure to both of said chambers, and means operated according to the rate of retardation of the vehicle for varying the pressure in one of said chambers without affecting the pressure in the other chamber.

14. In a vehicle brake system, in combination, a fluid pressure operated switch device having two chambers and operable upon supply of fluid under pressure to one or both of said chambers to effect an application of the brakes, means for establishing 25 a communication through which fluid under pressure may be supplied at an unrestricted rate to one of said chambers, means for establishing a separate communication through which fluid under pressure may be supplied at a restricted rate 30 to the other of said chambers, and means operated according to the rate of retardation of the vehicle for controlling one of said two communications.

15. In a vehicle brake system, in combination, a fluid pressure operated switch device having a plurality of chambers and operable upon supply of fluid under pressure to one or more of said chambers to effect an application of the brakes, and operable upon the variation of pressure in 40 one of said chambers to modify the degree of application of the brakes, means for effecting a supply of fluid under pressure to one or more of said chambers, and a retardation controller device for controlling the variation of pressure in 45 one of said chambers.

16. In a vehicle brake system, in combination, a brake controlling device having two chambers and operable upon supply of fluid under pressure to one of said chambers to effect an application 50 of the brakes to one degree and operable upon supply of fluid under pressure to both of said chambers to effect an application of the brakes to a different degree, manually operated means for effecting a supply of fluid under pressure to 55 both of said chambers, and means operated according to the rate of retardation of the vehicle for controlling the pressure of fluid in one of said two chambers.

17. In a vehicle brake system, in combination, 60 electro-responsive means for effecting and controlling the degree of application of the brakes, a fluid pressure operated brake control device having a plurality of chambers and operable upon supply of fluid under pressure to one or more of said chambers to control the operation of said electroresponsive means, means for effecting a supply of fluid under pressure to all of said chambers to effect the operation of said electroresponsive means to apply the brakes, a retardation 65 controller device operated according to the rate of retardation of the vehicle, and means responsive to operation of said retardation controller device for varying the pressure in one of said chambers.

18. In a vehicle brake system, in combination, 75

a brake controlling device having two chambers and operable upon supply of fluid under pressure to one or both of said chambers to effect an application of the brakes, manually operated means for effecting a supply of fluid under pressure to both of said chambers, means operated according to the rate of retardation of the vehicle for controlling the pressure in one of said chambers and operable at a chosen rate of retardation to 10 close communication between said one chamber and said manually operated means, and means operable to permit release of fluid under pressure from both of said chambers by manipulation of said manually operated means regardless of the 15 operation of said retardation controlled means.

19. In a vehicle brake system, in combination, electrically controlled valve means for controlling the application and the release of the brakes, a fluid pressure operated switch device having two chambers and operable upon supply of fluid under pressure to one of said chambers to effect an application of the brakes to a chosen degree corresponding to the pressure in said chamber, and operable upon supply of fluid under pressure to the other of said chambers to effect an 25 increase in the degree of application of the brakes above that corresponding to the pressure in said first chamber, means for effecting a supply of fluid under pressure to both of said chambers to initiate an application of the brakes, and means 30 operated according to the rate of retardation of the vehicle for varying the pressure of fluid in said other chamber, the variation of pressure in said other chamber being ineffective to reduce the degree of application of the brakes below 35 said chosen degree.

20. In a vehicle brake system, in combination, a brake controlling device having two chambers and operable upon supply of fluid under pressure to both of said chambers to effect an application 40 of the brakes and operable upon variation of pressure in either of said chambers to vary the degree of application of the brakes, means for forming a communication to one of said chambers through which fluid under pressure may be supplied at an 45 unrestricted rate, and means for forming a communication to the other of said chambers through which fluid under pressure may be supplied at a restricted rate, and means operated according to the rate of retardation of the vehicle for controlling said second communication and operable at a chosen rate of retardation to rapidly reduce the pressure of fluid in said second chamber.

21. In a vehicle brake system, in combination, 55 valve means for controlling the application and the release of the brakes, means including a control device having a plurality of chambers to which fluid under pressure is supplied for controlling the operation of said valve means, means for effecting a supply of fluid under pressure to said chambers to effect the operation of said valve means to apply the brakes, a retardation controller device for controlling the pressure of fluid in one of said chambers, and means controlled with respect to the speed of the vehicle for independently controlling the operation of said valve means.

22. In a vehicle or train brake system, in combination, valve means for controlling the application and the release of the vehicle or train 70 brakes, electroresponsive means including a fluid pressure operated switch device having a plurality of chambers and operable upon supply of fluid pressure to said chambers to effect the operation of said valve means to apply the brakes, manually 75

operated means for effecting a supply of fluid under pressure to one of said chambers rapidly and a supply of fluid under pressure to another of said chambers more slowly, to effect an application of the brakes, inertia operated means for controlling the pressure of fluid in said last mentioned chamber, to vary the degree of application of the brakes, and means controlled by the speed of the vehicle for also varying the degree of application of the brakes.

23. In a vehicle brake system, in combination, magnet valve devices for controlling the application and the release of the brakes, a fluid pressure operated switch device having a plurality of chambers and operable upon variation of pressure in one or more of said chambers to control the operation of said magnet valve devices, manually operated means for controlling the supply of fluid under pressure to and its release from said plurality of chambers, means operated according to the rate of retardation of the vehicle for controlling the pressure of fluid in one of said chambers, and means controlled by the speed of the vehicle for varying the degree of application of the brakes independently of variation of pressure in any of said chambers.

24. In a vehicle brake system, in combination, valve means for controlling the application and the release of the brakes, means including a fluid pressure operated switch device for controlling the operation of said valve means, means operated according to the rate of retardation of the vehicle for controlling the operation of said switch device, and means controlled by the speed of the vehicle for also controlling the operation of said valve means.

25. In a vehicle brake system, in combination, valve means for controlling the application and the release of the brakes, means including a fluid pressure operated switch device for controlling the operation of said valve means, means operated according to the rate of retardation of the vehicle for controlling the operation of said switch means, and means controlled by the speed of the vehicle for also controlling the operation of said valve means and operable as the speed of the vehicle diminishes due to application of the brakes to cause said valve means to reduce the degree of application of the brakes.

26. In a vehicle brake system, in combination, fluid pressure operated valve means for controlling the application and the release of the brakes, means for forming a communication through which fluid under pressure is supplied to effect the operation of said valve means, means including a fluid pressure operated switch device for controlling the supply of fluid under pressure to and its release from said communication, means operated according to the rate of retardation of the vehicle for exercising a limited control over the operation of said switch device, and means operated by and in response to the speed of the vehicle for controlling the manner in which the pressure of fluid supplied to said communication acts upon said valve means.

27. In a vehicle brake system, in combination, a fluid pressure operated switch device for controlling the application and the release of the brakes, said switch device having two movable abutments of different effective pressure areas, one of said abutments being subject to fluid pressure in a first chamber and the other of said abutments being subject on one side to fluid pressure in said first chamber and on the other side to fluid pressure in a second chamber, means for

forming a communication to said second chamber through which fluid under pressure may be supplied at an unrestricted rate, means for forming a communication to said first chamber through which fluid under pressure may be supplied at a restricted rate, and a retardation controller device for controlling said second communication. 5

28. In a vehicle brake system, in combination, a fluid pressure operated switch device for controlling the application and the release of the brakes, said switch device having two diaphragms of different effective pressure areas, said two diaphragms being so constructed and arranged as to form therebetween a first chamber and to one side of the smaller of said two diaphragms a second chamber, means for forming a communication through which fluid under pressure may be supplied at an unrestricted rate to said second chamber, means for forming a communication to said first chamber including a choke and a timing reservoir associated therewith, and a retardation controller device for controlling the pressure of fluid in said first chamber only. 10 15 20

29. A control device for a fluid pressure brake comprising, in combination, a plurality of contacts, a plurality of movable abutments, means cooperating with said abutments to form three pressure chambers, one of said chambers being between two of said abutments, another of said chambers being to one side of one of said two abutments, and the third of said chambers being to one side of a still different abutment, and means for operating said contacts in response to movement of said abutments upon variation of pressure in one or more of said chambers. 25 30 35

30. A control device for fluid pressure brakes comprising, in combination, a casing, three diaphragms coacting with said casing to form three pressure chambers, two of said diaphragms being of equal pressure area and the third of said diaphragms being of lesser effective pressure area than the other two, a first of said chambers being between one of the large diaphragms and the small diaphragm, the second of said chambers being to one side of the small diaphragm, and the third of said chambers being to one side of the third diaphragm, a plurality of normally opened contacts, and means associated with said three diaphragms and so constructed and arranged that upon supply of fluid under pressure to one or both of said first and second chambers said contacts are closed and upon supply of fluid under pressure to said third chamber at least some of said contacts are opened. 40 45 50

31. In a vehicle brake system, a combination, 55 a control device having a plurality of chambers to which fluid under pressure is supplied to effect an application of the brakes, means for manually effecting a supply of fluid under pressure to both of said chambers, automatic means operated upon a decrease of fluid pressure therein for effecting a supply of fluid under pressure to both of said chambers, and means operated according to the rate of retardation of the vehicle for controlling the pressure of fluid in one of said chambers regardless of whether supplied by said manually operated means or said automatic means. 60 65

32. In a vehicle brake system, in combination, electroresponsive means for controlling the application and the release of the brakes, means including a fluid pressure operated switch device having two chambers, for controlling the operation of said electroresponsive means, manually operated means for effecting a supply of 70 75

fluid under pressure to both of said chambers, a normally charged pipe, an automatic valve device operated upon a predetermined reduction of pressure in said normally charged pipe for effecting a supply of fluid under pressure to both of said chambers, and a retardation controller device for controlling the pressure of fluid in one of said chambers regardless of whether supplied by said manually operated means or said automatic valve device.

33. In a vehicle brake system, in combination, a control device for controlling the application and the release of the brakes, said control device having two chambers and being operable upon supply of fluid under pressure to one of said chambers to effect an application of the brakes to one degree and operable upon supply of fluid under pressure to both of said chambers to effect an application of the brakes to an increased degree, manually operated means potentially effective to effect a supply of fluid under pressure to both of said chambers, automatic means operable upon a reduction of pressure therein to potentially effect a supply of fluid under pressure to both of said chambers, valve means for selecting between said potential sources of supply, and means for restricting the rate of supply to one of said chambers regardless of from which source the supply is effected.

34. In a vehicle brake system, in combination, a fluid pressure operated switch device for controlling the application and the release of the brakes, said switch device having two chambers and operable upon the supply of fluid under pressure to one of said chambers to effect an application of the brakes to one degree and operable upon the supply of fluid under pressure to both of said chambers to effect an application of the brakes to an increased degree, manually operable means for effecting a supply of fluid under pressure to both of said chambers, automatic valve means for effecting a supply of fluid under pressure to both of said chambers, valve means for selecting between said two supplies, means for delaying the supply of fluid under pressure to one of said chambers, and a retardation controller device for controlling the degree of pressure in one of said chambers according to the rate of retardation of the vehicle.

35. In a vehicle brake system, in combination, valve means for controlling the application and the release of the brakes, speed controlled means operated according to the speed of the vehicle, retardation control means operated according to the rate of retardation of the vehicle, means operative during normal service or emergency applications of the brakes to cause the degree of application to be under the joint control of said speed control means and said retardation control means, and means operative upon effecting an auxiliary service application of the brakes for causing said speed controlled means only to control the degree of the application.

36. In a vehicle brake system, in combination, speed controlled means operated by and in response to the speed of the vehicle, retardation controlled means operated by and in response to the rate of retardation of the vehicle, means for effecting an application of the brakes by straight air operation or by automatic operation, and means for causing all straight air applications and automatic emergency applications of the brakes to be under the joint control of said speed controlled means and said retardation controlled means, and for causing automatic service

applications of the brakes to be under the control of said speed controlled means only.

37. In a vehicle brake system, in combination, valve means for controlling the application and the release of the brakes, means for forming a communication through which fluid under pressure is supplied to effect the operation of said valve means, speed controlled means for controlling the action of the pressure in said communication upon said valve means, means including a fluid pressure operated switch device for controlling the supply of fluid under pressure to said communication, a retardation controller device for controlling operation of said switch means, a normally charged pipe, and a valve device operated upon a reduction of pressure in said pipe for effecting a supply of fluid under pressure to said communication at a time when said switch device is not operated or is ineffective to operate.

38. In a fluid pressure brake system, in combination, a brake cylinder, valve means for controlling the supply of fluid under pressure to and its release from said brake cylinder, speed controlled means operated by and in response to the speed of the vehicle for controlling the operation of said valve means, electroresponsive means including a fluid pressure operated switch device for also controlling the operation of said valve means, said switch device having a plurality of chambers to which fluid under pressure is supplied to effect the application of the brakes and in which the pressure of fluid is varied to vary the degree of application of the brakes, manually operable means for effecting a supply of fluid under pressure to said chambers, automatic valve means for also effecting a supply of fluid under pressure to said chambers, and retardation control means for controlling the pressure of fluid in one of said chambers, said retardation control means being ineffective to reduce brake cylinder pressure below a value permissible according to the operation of said speed controlled said last mentioned means.

39. In a vehicle brake system, in combination, a first valve means for controlling the application and the release of the brakes, speed controlled means operated by and in response to the speed of the vehicle for controlling said first valve means, a second valve means for also controlling the operation of said first valve means, and means including a retardation controller device for controlling the operation of said second valve means.

40. In a vehicle brake system, in combination, a valve device for controlling the application and the release of the brakes, said valve device having a plurality of chambers to which fluid under pressure is supplied to effect an application of the brakes, means for effecting a supply of fluid under pressure to said chambers, and a retardation controller device for varying the pressure of fluid in one of said chambers.

41. In a vehicle brake system, in combination, valve means for controlling the application and the release of the brakes, said valve means having a first chamber to which fluid under pressure is supplied to effect an application of the brakes to one degree, and having a second chamber to which fluid under pressure is also supplied to effect an application of the brakes to an increased degree, means for effecting a supply of fluid under pressure to both of said chambers, and a retardation controller device for varying the pressure of fluid in one of said chambers, said retardation controller device being ineffect-

tive to reduce the degree of application of the brakes below that corresponding to the effect of the pressure of fluid in said other chamber.

42. In a vehicle brake system, in combination, 5 a valve device for controlling the application and the release of the brakes, said valve device having a first chamber to which fluid under pressure is supplied to effect an application of the brakes to a chosen degree, and having a second chamber to 10 which fluid under pressure is supplied to increase the degree of application of the brakes above said chosen degree, means forming a first communication to said first chamber through which fluid under pressure is supplied at an unrestricted rate, means forming a second communication to 15 said second chamber through which fluid under pressure is supplied at a restricted rate, and a retardation controller device for controlling said second communication.

20 43. In a vehicle brake system, in combination, a valve device for controlling the application and the release of the brakes, said valve device having two movable abutments of different effective pressure areas, one of said abutments being responsive to fluid pressure in a first chamber, and the other of said abutments being responsive to fluid pressure in a second chamber, means forming an unrestricted communication leading to 25 said first chamber, means forming a restricted communication leading to said second chamber, and a retardation controller device for controlling one of said two communications.

30 44. In a vehicle brake system, in combination, a first valve means for controlling the application 35 and the release of the brakes, a second valve means for also controlling the application and the release of the brakes, speed controlled means, retardation controlled means operated according to the rate of retardation of the vehicle, and 40 means whereby said first valve means is controlled only by said speed controlled means, and whereby both said first valve means and said second valve means are controlled by said retardation controlled means.

45 45. In a vehicle brake system, in combination, a valve means for controlling the application and the release of the brakes, said valve means having two unconnected movable abutments each of which has a chamber to one side thereof, 50 means forming an unrestricted communication to one of said chambers, means forming a different communication to another of said chambers, means associated with said second communication for delaying flow of fluid under pressure 55 therethrough, and a retardation controller device for controlling the flow of fluid through and the release of fluid from one of said communications.

46. In a vehicle brake system, in combination, 60 a valve means for controlling the application and the release of the brakes, said valve means having a plurality of movable abutments with a chamber to one side of each, and being operable to control the operation of said valve means according to which of said chambers has fluid 65 under pressure supplied thereto, manually operable means for supplying fluid under pressure to said chambers, automatic valve means operable upon a reduction of pressure therein for supplying fluid under pressure to said chambers, and a retardation controller device for controlling the 70 pressure of fluid supplied to one of said chambers regardless of whether supplied by said manually operated means or said automatic valve means.

47. In a vehicle brake system, in combination, 75 a valve device for controlling the application and

the release of the brakes, said valve device having two diaphragms of different effective pressure areas, the larger of said diaphragms having a first chamber to one side thereof, and the smaller of said diaphragms having a second chamber to one side thereof, means for effecting a supply of fluid under pressure to said second chamber to effect an application of the brakes to a chosen degree, means for also effecting a supply of fluid under pressure to said first chamber to increase the degree of application of the brakes to a maximum value above said chosen degree, and a retardation controller device operable to vary the pressure in said first chamber whereby to vary the application of the brakes between said maximum value and said chosen degree. 10 15

48. The method of controlling the brakes for vehicles or trains, which comprises, initiating an application of the brakes, establishing the initial 20 braking force according to the speed of the vehicle or train, and then varying the braking force jointly according to both the speed and the rate of retardation of the vehicle or train.

49. The method of controlling the brakes for a 25 vehicle or train, which comprises, initiating an application of the brakes, establishing the initial braking force according to the speed of the vehicle or train, reducing the initial braking force in steps as the speed of the vehicle or train 30 diminishes, and varying the degree of braking force between each of said steps as required to prevent the rate of retardation from substantially exceeding a chosen value.

50. The method of controlling the brakes for 35 vehicles and trains, which comprises, initiating an application of the brakes, and varying the degree of the application jointly with respect to both the speed and the rate of retardation of the vehicle such that the degree of the application 40 is variable over a fixed range above a predetermined vehicle speed, and variable over a fixed but different range below said predetermined speed.

51. The method of controlling the brakes for 45 vehicles or trains, which comprises, initiating an application of the brakes, and controlling the degree of the application partly in response to vehicle speed and partly in response to the rate of retardation of the vehicle such that 50 there is established for each of a plurality of speed ranges a different but fixed set of upper and lower limits between which the degree of the application is varied.

52. The method of controlling the brakes for 55 vehicles or trains, which comprises, initiating an application of the brakes, establishing the initial degree of the application according to the speed of the vehicle or train, and thereafter controlling the degree of the application jointly in response 60 to both the vehicle speed and the rate of retardation of the vehicle or train such that there is established for each of a plurality of speed ranges a different upper and lower limit between which the degree of the application may be varied. 65

53. In a vehicle or brake system, in combination, means operable to effect an application of the brakes to each of plurality of certain different uniform degrees of braking force, means responsive to the speed of the train for so controlling said brake application means as to cause it to establish different ones of said certain degrees of braking force for different train speeds, and retardation control means for so controlling said brake control means as to cause it to establish 70 75

lish for a given rate of retardation different degrees of braking force for different train speeds.

54. In a vehicle or train brake system, in combination, means for effecting an application of the brakes, speed controlled means, means operated according to the rate of retardation of the vehicle or train, and means so constructed and arranged that said speed controlled means establishes the initial degree of application of the 10 brakes, while said retardation controlled means is thereafter operable to modify said initial degree of application, and both said speed controlled means and said retardation controlled means subsequently cooperate to jointly modify the degree of the application as the speed of the vehicle or train diminishes.

55. In a vehicle or train brake system, in combination, means for effecting an application of the brakes, speed controlled means, inertia 20 means, and means so constructed and arranged that either or both of said speed controlled means and inertia means may be effective at any time during an application to control the degree of the application.

56. In a vehicle brake system, in combination, means for effecting an application of the brakes, means operated according to the rate of retardation of the vehicle for controlling the degree of application of the brakes, and means operated 30 according to the speed of the vehicle for decreasing the range over which said retardation controlled means may vary the degree of application of the brakes.

57. In a vehicle brake system, in combination, 35 a brake cylinder, means for establishing a communication through which fluid under pressure is supplied rapidly to effect a rapid supply of fluid under pressure to said brake cylinder, means for establishing a different communication through 40 which fluid under pressure is supplied slowly to slowly increase the degree of the brake cylinder pressure, inertia operated means for controlling the supply of fluid under pressure through one of said communications, and speed controlled 45 means for controlling brake cylinder pressure regardless of through which communication fluid under pressure is supplied to establish brake cylinder pressure.

58. In a vehicle brake system, in combination, 50 a brake control device having two chambers and operable upon supply of fluid under pressure to either or both of said chambers to effect an application of the brakes, means for effecting a supply of fluid under pressure to both of said chambers, and inertia operated means for controlling the pressure in one of said chambers.

59. In a vehicle brake system, in combination, 55 a brake cylinder, a valve device for controlling

the supply of fluid under pressure to and its release from said brake cylinder, said valve device having a plurality of chambers to and from which fluid under pressure is supplied and released to effect the supply to and release from 5 said brake cylinder, means for effecting a supply of fluid under pressure to said plurality of chambers, and an inertia operated device for controlling the pressure of fluid in at least one of said chambers.

60. In a vehicle or train brake system, in combination, means for effecting an application of the brakes, speed controlled means, inertia operated means, means controlled by said speed controlled means for establishing the initial degree 15 of application of the brakes according to which of a plurality of speed ranges the vehicle or train is traveling in at the time of initiating the application, and means controlled by said inertia operated means for varying the degree of the application 20 over a range which bears a substantially constant relation to the initial degree of the application as established by said speed controlled means.

61. In a vehicle brake system, in combination, 25 a brake cylinder, a control pipe to which fluid under pressure is supplied to effect an application of the brakes, inertia operated means for controlling the degree of straight air pipe pressure, means responsive to straight air pipe pressure 30 for controlling the supply of fluid under pressure to and its release from said brake cylinder, and speed controlled means for controlling said last mentioned means.

62. In a vehicle brake system, in combination, 35 a brake cylinder, a straight air pipe, means for effecting a supply of fluid under pressure to said straight air pipe to effect an application of the brakes, a retardation controller device for controlling straight air pipe pressure, valve means 40 responsive to straight air pipe pressure for controlling the supply of fluid under pressure to and its release from said brake cylinder, and speed controlled means operated according to the speed 45 of the vehicle for controlling the operation of said valve means.

63. In a vehicle or train brake system, in combination, means for establishing a control pressure to effect an application of the brakes, speed controlled means, means operated according to 50 the rate of retardation of the vehicle or train, means so constructed and arranged that said speed controlled means and said retardation controlled means cooperate to jointly control the degree of application of the brakes, and a switch 55 device operated by said control pressure for rendering said speed controlled means effective.

ELLIS E. HEWITT.

CERTIFICATE OF CORRECTION.

Patent No. 2,110,706.

March 8, 1938.

ELLIS E. HEWITT.

It is hereby certified that error appears in the printed specification of the above numbered patent requiring correction as follows: Page 11, second column, line 11, claim 6, for the word "controlling" read controlled; page 12, second column, line 73, claim 22, after "fluid" insert under; page 14, second column, line 43, claim 38, strike out the words "said last mentioned; and that the said Letters Patent should be read with this correction therein that the same may conform to the record of the case in the Patent Office.

Signed and sealed this 27th day of September, A. D. 1938.

Henry Van Arsdale

(Seal)

Acting Commissioner of Patents.
